UNITED STATES PATENT OFFICE.

ISEDORE GREENGUS, OF PROVIDENCE, RHODE ISLAND.

DESIGN FOR A CLOCK CASE.

Application filed October 12, 1927. Serial No. 23,737. Term of patent 7 years.

To all whom it may concern:

Be it known that I, ISEDORE GREENGUS, a citizen of the United States, residing at 141 Dudley Street, Providence, of the county of Providence and State of Rhode Island, have invented a new, original, and ornamental Design for a Clock Case, of which the following is a specification, reference being had to the accompanying drawing, forming a part thereof.

Fig. 1 is a front elevation of a clock case embodying my design.

Fig. 2 is a side elevation thereof.

I claim:

The ornamental design for a clock case substantially as shown.

In testimony whereof I affix my signature.

ISEDORE GREENGUS.
